FIG. 1 is a perspective view of a shelf unit showing my new design;

FIG. 2 is a top plan view thereof;

FIG. 3 is a front elevational view thereof, the front and rear views being the same;

FIG. 4 is a side elevational view thereof, the opposite sides being the same;

FIG. 5 is an enlarged cross-sectional view of one of the vertical corner posts taken along the line 5-5 of FIG. 1;

FIG. 6 is an enlarged fragmentary sectional view taken along the line 6-6 of FIG. 3 illustrating in a horizontal plane the juncture of a pair of horizontal brace members with a vertical corner post; and

FIG. 7 is an enlarged fragmentary sectional view taken along the line 7-7 of FIG. 3 illustrating in a vertical plane the juncture of a pair of horizontal brace members with a vertical corner post.

The design is characterized by horizontally disposed brace members having their opposite ends engaging the

beaded edges of vertical corner posts which are cruciform in cross-section, the brace members being arranged in opposing pairs for selectively supporting shelves which may be transparent or opaque.

I claim:

The ornamental design for a shelf unit, as shown and described.
